UNITED STATES PATENT OFFICE.

ALBERT E. CAUGHEY, OF OMAHA, NEBRASKA, ASSIGNOR OF ONE-HALF TO
J. E. HOLLENBECK, OF POTTAWATTAMIE COUNTY, IOWA.

RAILROAD SIGNAL AND ALARM.

SPECIFICATION forming part of Letters Patent No. 717,075, dated December 30, 1902.

Application filed December 12, 1901. Serial No. 85,581. (No model.)

To all whom it may concern:

Be it known that I, ALBERT E. CAUGHEY, residing at 2541 Davenport street, Omaha, in the county of Douglas and State of Nebraska, have invented certain useful Improvements in Railroad Signals and Alarms; and I do hereby declare that the following is a full, clear, and exact description of the invention, such as will enable others skilled in the art to 5 which it appertains to make and use the same, reference being had to the accompanying drawings, which form a part of this specification.

This invention relates to a new and novel 15 track mechanism to be used in connection with a suitable alarm.

The aim of my invention is to provide a mechanism adapted to be placed adjacent the track, to be operated by the wheels of the vehicles passing over the same to form an electric contact to operate a suitable alarm, as 20 will be described more fully hereinafter.

In the accompanying drawings I have shown in Figure 1 a track mechanism with 25 portions removed. Fig. 2 discloses the track mechanism as depressed to form a contact, while Fig. 3 discloses a top view of my device.

My invention embodies, essentially, a narrow topless housing A, within which at one 30 point is secured a supporting-pin 13. To this pin is secured the spring-actuated lever H, which above is provided with the enlarged head 16, forming a seating, within which is held the upper end of the coil-spring F, pressing 35 below upon the bottom b of the housing A. Pivotal secured to this spring-actuated lever H, approximately midway, by means of the screw 9, is the toggle-bar K, which at its upper end, by means of the screw 8, is secured 40 to the striker end C, as shown. This striker-lever C has its remaining end 3 secured by means of a screw 4 to a bow-spring 5, secured below to a block 7 by means of the pins 6. Positioned below the end 3 of this 45 striker-lever C is a block B, provided with the seating 2, into which the end 3 works when the striker end C is depressed. Extending from near the upper end of the lever H is a push-bar 15, secured by means of the 50 screw 14, and this push-bar passes through

an opening within the partition 16', passing transversely across the housing. Secured within the compartment formed by means of the end a and the partition 16' are the two insulating-blocks f, positioned one above the other, and to the upper bar f is secured an inverted-J-shaped spring D, while to the lower block f is secured a smaller J-shaped spring E, the end of these spring-terminals being adjacent one another, as shown in Fig. 1. Extending from the spring D is a suitable track-wire W, while extending from the remaining spring E is a second track-wire V, as shown. Positioned adjacent the spring-lever H is a stop 12, provided with the extension 10, 65 against which the lever H works.

When the instrumentalities have been properly arranged, the operation of my device will be as follows: Should a train approach from the direction as indicated by the arrow x in Fig. 2, the wheel x' will encounter the striker end C and depress the same against the tension of spring 5 to force this lever into the seating 2 of the block B. This depression of the lever C will push forward the toggle K, and this in turn will depress the spring-actuated lever H against the tension of the spring F, and this lever H in turn will push forward the push-bar 15 to bring into contact the electric terminals D and E with a sliding movement, which would have a tendency to keep these contact-points bright. The end of the push-bar 15 is provided with suitable insulating material c, as shown. As soon as these terminals D and E are drawn together 85 the track-wires will be connected to operate any suitable electric gong used in connection with my device.

Any electric signal which is operated when a circuit is formed may be used with my device. 90

Having thus described my said invention, what I claim as new, and desire to secure by United States Letters Patent, is—

The combination with a suitable housing, 95 of a pivotally-supported lever, a spring to normally force one end of said lever upward, an angular toggle-bar movably secured to said lever, said toggle-bar normally projecting beyond the top of aforesaid housing, a 100

spring to support the remaining end of said angular toggle-bar, a seating below the spring-supported end of said toggle-bar, a push-bar secured to aforesaid lever, a spring-terminal positioned adjacent said push-bar, and a second spring-terminal positioned adjacent said first-mentioned terminal, so arranged that in

depressing aforesaid toggle-bar, said terminals may be brought into contact, as and for the purpose set forth.

ALBERT E. CAUGHEY.

In presence of—
J. E. HOLLENBECK,
GEO. W. SUES.
